UNITED STATES PATENT OFFICE.

JOSEPH PARR, OF RIVER HOMES, WASHINGTON.

STEP-LADDER.

1,146,094.

Specification of Letters Patent. Patented July 13, 1915.

Application filed August 8, 1914. Serial No. 855,758.

To all whom it may concern:

Be it known that I, JOSEPH PARR, a citizen of the United States, residing at River Homes, in the county of Lincoln and State 5 of Washington, have invented new and useful Improvements in Step-Ladders, of which the following is a specification.

This invention is an improved ambulant step ladder adapted for use in picking and 10 packing fruit such as apples, peaches or the like and also adapted for use in house painting and other analogous purposes and embodying a press for holding a box while 15 the same is being filled with fruit and for pressing down the fruit in the box and fitting the cover thereon.

The invention consists in the construction, combination and arrangement of devices hereinafter described and claimed.

20 In the accompanying drawings: Figure 1 is an elevation of a step ladder constructed in accordance with my invention. Fig. 2 is a similar view at right angles to Fig. 1. Fig. 3 is a detail plan, showing the press, 25 the standards being indicated in section. Figs. 4 and 5 are detail sectional views on the planes indicated by the lines *a—a* and *b—b* respectively of Fig. 3. Fig. 6 is a detail vertical sectional view of the upper portion of the foldable ladder. Fig. 7 is a detail plan of the box supporting tray. Fig. 8 is a detail perspective view of one of the 30 triangular plates employed in the construction of the foldable ladder.

35 In accordance with my invention I provide an axle 1 which has a pair of supporting wheels 2. A pair of bars 3 are secured to the under side of the axle at points a suitable distance from the end of said bars and 40 the longer ends of the bars are shaped to form handles 4. Standards 5 are secured to the axle and to the bars 3. Cross bars 6 are also secured on the bars 3. Oppositely extending and inclined braces 7 have their 45 lower ends secured to the cross bars. One pair of standards are connected together by a cross beam 8. One pair of braces 7 are connected together by a cross beam 9. An elevated floor or platform 10 is secured on 50 the cross beams 8—9 and has a cross beam 11 on its under side at the end opposite the cross beam 9. The ends of the cross beam project beyond the sides of the floor or platform and support running boards 12. Side 55 boards 13 connect the upper ends of the

standards and an end board or wall 14 connects one end of the side boards.

A fixed ladder or ground ladder 15 is provided which comprises spaced side bars 16 that are secured to the bars 3 and to one 60 of the running boards and one of the side boards 13. These bars 16 are inclined and extend below as well as above the bars 3 so that their lower ends bear on the ground and serve to hold the bars 3 and the elevated 65 platform in horizontal position. The steps 17 of the ladder 15 are secured to the inclined bars 16 and one of said steps is also secured on the bars 3.

A pair of substantially semi-circular racks 70 18 are secured to the standards and certain of the braces under the elevated platform and are provided with notches 19. A foldable and shiftable step ladder 20 is mounted above the platform and comprises a member 75 21 and a member 22. The member 21 comprises a pair of side bars 23 which are pivotally mounted on a pivot rod 24 that extends through the side boards 13, the lower ends of said bars 23 operating in the racks 80 18 and being provided with guides 25 which bear on the inner sides of said racks. These bars 23 are connected together by steps 26. Substantially triangular plates 27 are secured on the ends of the steps and one end 85 of each plate is arranged on the inner side of one of the bars 23 and pivoted thereto as at 28. The member 22 comprises a pair of bars 29 which are pivotally mounted near their lower ends as at 30 on the inner sides 90 of the side boards 13. The plates 27 are also pivotally secured as at 31 on the inner sides of said bars 29. Hence the ladder 20 may be arranged in folded horizontal position within the side walls 13 and on the 95 floor or platform as indicated in dotted lines in Fig. 1 or may be arranged in a vertical position or at any desired inclination as shown in full lines in said figure. To secure the ladder in adjusted position I provide 100 the member 20 with a rock shaft 32 which may form the pivot of two of the plates and the ends of which are outturned to form rock arms 33. These rock arms are connected to bolt rods 34 which operate in suitable guides 35 and may be projected from the lower ends of the bars 23 and engaged with any of the notches 19 of the racks 18 as will be understood.

The shorter ends of the bars 3 which pro- 110

ject from one side of the axle support a box press which I will now describe. Said ends of the arm 3 support a cross bar 37. A bar 38 is secured at right angles to said bar 37 5 and at a point to one side the center thereof. A pair of bowed springs 39 are secured near the ends of the bar 37. A presser board 40 is arranged below the frame formed by the bars 3—37—38 and a brace bar 41 and said 10 presser board is connected as at 42 to the ends of the springs 39. Said springs while serving to normally raise the presser board also permit it to be moved downwardly as will be understood. I also provide a pair of 15 vertical rectangular clamping frames 43—44 the inner sides of which are arranged to slide vertically in guides 45 and the clamping frame 44 is also pivotally mounted in its guide for angular movement in a horizontal 20 plane. The presser board is provided on its under side with bars 46—47. The lower side of the clamping frame 43 is secured to the bar 46. The clamping frame 44 is pivoted at one side to the bar 47 as at 48 and is arranged to swing below that portion of the 25 presser board which projects beyond said bar 47. A locking rack 49 extends downwardly from the bar 38. On the upper side of the presser board, at the center thereof, is 30 a bar 50 which has a slot 51. A lever 52 is loosely connected as at 53 under the center of the axle and extends out through the slot 51 and bears on the bar 50 and has a keeper plate 54 which is adapted to engage the locking rack 49. Said lever enables the presser board to be moved downwardly against the 35 tension of its supporting springs so as to draw the clamping frames downwardly and over a box placed on the press as will be understood. Said lever is connected by a link rod 55 to the frame 44 to enable said lever to 40 swing said frame outwardly or inwardly to disengage the same from or disengage the same with one end of a box as will be understood. A box supporting tray 56 is loosely 45 connected as at 57 to the bar 3 nearest the clamping frame 43. This box supporting tray is provided with cleats on its under side and indicated at 58—59 and is cut away at 50 one of its inner corners as at 60 to clear the free side of the clamping frame 44 (see Fig. 7). On the upper side of said box supporting tray or table is a trough-shaped cleat 61 to engage one of the cleats under the bottom 55 of a packing box for holding fruit and near the opposite end of said tray or table is a cleat 62.

When my step ladder is used in picking fruit from trees and it is desired to pack the 60 fruit in boxes as fast as it is picked one of the fruit boxes will be placed on the tray or table and the lever will be operated to swing the clamping frame 44 outwardly so that the

table or tray can be swung outwardly on its pivot and caused to rest in an inclined position on the outer end of the lever and also on the bars 3 to support the box at the required inclination to facilitate the orderly arrangement and packing of the fruit in tiers therein. When the box is filled the tray 65 or table is then swung inwardly and caused to rest squarely on the frame formed by the bars 3—37—38 and brace 41, the lever is moved to a position substantially parallel with the bars 3 so as to close the clamping 70 frame 44 around one end of the box and when the top has been placed on the box the lever is depressed thereby causing the presser board to be moved downwardly against the tension of its springs and to draw the 75 clamping frames downwardly and cause said frames to engage the box top and press the same firmly down on the fruit, packing the latter in the box and holding the top thereon in position to be nailed or otherwise fastened. By engaging the keeper of the lever with the locking rack the lever may be 80 locked at any desired adjustment to hold the presser board and the clamping frames in the desired clamping position. 85

Having thus described my invention, I claim:—

1. A step ladder of the class described comprising an ambulant frame having an elevated platform, a ladder at one end of the 90 frame leading to said platform and a foldable ladder pivotally mounted on the platform and arranged at right angles to the first-named ladder.

2. A ladder of the class described comprising an axle having supporting wheels, a pair of handle bars attached to the axle, a fixed ladder having its side members secured on said handle bars, a frame on the axle and handle bars, a platform mounted on said 100 frame and arranged above and parallel with the axle and a foldable ladder pivotally mounted on said platform.

3. A ladder of the class described comprising an axle having supporting wheels, a pair of handle bars attached to the axle, a fixed ladder having its side members secured to said handle bars, a frame on the axle and handle bars, a platform mounted on said 110 frame and arranged above and parallel with the axle and a foldable ladder pivotally mounted on said platform, said platform having side boards and end boards and being also provided with running boards at the outer sides of said side boards. 115

In testimony whereof I affix my signature in presence of two witnesses.

JOSEPH PARR.
